UNITED STATES PATENT OFFICE.

WILHELM B. BRONANDER, OF MONTCLAIR, NEW JERSEY.

INTERNAL-COMBUSTION ENGINE.

Application filed September 23, 1920, Serial No. 412,224. Renewed April 2, 1927.

This invention relates to improvements in internal combustion engines, and its object is to improve the construction of such engines, especially of those which are operated with comparatively slow burning oils for fuel. More specifically its object is to provide a double cylinder engine of the two cycle type with two pistons in each cylinder in which the pistons control the inlet and exhaust ports, and with novel mechanism interconnecting the pistons which is arranged to move the pistons in such mutual relation as to produce the desired cycle of operation. Another object is to provide a simple mechanism for producing long piston displacement with a short eccentricity of the crank shaft.

These and other objects of the invention will appear in the following specification in which I will describe the invention and the novel features of which will be set forth in appended claims.

Referring to the drawings:

Figure 1 is a sectional end elevation of an engine which is made according to and embodies this invention.

Figure 2 is a sectional side elevation of the same.

Figure 3 is a sectional plan view of the same engine, the section being taken on the line 3—3 of Fig. 1.

Figures 4 to 9 are diagrams illustrating the cycle of operation of the engine.

Figure 10 is a sectional end elevation of a V-type engine with four cylinders and with its pistons connected with a common crank shaft.

Like characters of reference designate corresponding parts in all the figures of the drawings.

10 designates a base in which the shaft 11 is supported. This has a pair of crank pins 12, 12 of like angularity and eccentricity, spaced apart as shown. Connecting rods 13, 13 extend upwardly from these crank pins.

45 These are T-shaped as transverse projections 14 and 15 extend outwardly from their upper ends (Fig. 1). The transverse extensions are connected by cross rods 16 and 17.

Two cylinders 20 and 30 are affixed to the base with the division wall 21 between them directly over the shaft 11. This wall is

shorter than the cylinders so that the latter are interconnected at their ends by chambers 22 and 23. Spaced inlet ports 24, 25 are provided in the cylinder 20, and spaced exhaust ports 34, 35 are provided in the cylinder 30.

Spaced pistons 26, 27 in the cylinder 20 are rigidly connected by a rod 28. Similar pistons 36, 37 in cylinder 30 are connected by a rod 38. The rod 17 passes through slots 39 in the cylinder 30 and is pivotally connected with the rod 38. The rod 16 passes through slots 29 in the other cylinder and is slidably connected with rod 28. 32, 32 are oil inlet ports leading into the chamber 22 and 33, 33 are oil inlet ports leading into the chamber 23.

With this structure described and referring to the diagrams Figs. 4 to 9, the operation will be described. In Fig. 4, the charge is firing in the lower chamber 23 and the upper chamber is being scavenged. The latter result is accomplished by admitting air under pressure into cylinder 20 through ports 24 which air passes through chamber 22, and the upper part of cylinder 30 and out through ports 34.

Assuming the direction of rotation to be that indicated by the arrows A, the movement of the crank pins from the position shown in Fig. 4 to that shown in Fig. 5, will tilt the cross arm formed by the projections 14 and 15 to raise the piston 36 without materially affecting the position of the piston 26. Piston 36 then closes the exhaust ports 34 while the inlet ports 24 are still open.

A slight further movement of the crank shaft raises piston 26 to close the inlet ports. This action results in trapping some of the compressed air in the cylinders 20, 30 and the chamber 22. This is further compressed by the upward movement of the pistons.

In this compression step it is to be noted that the movement of piston 36 is faster than that of piston 26 until the pistons reach the positions in which they are shown in Fig. 6.

After this the piston 26 rises still further (Fig. 7) and makes the final compression. At about the point of final compression, fuel oil is injected under pressure and is ignited by the heat generated by the compression.

This drives pistons 26, 36 downwardly (Figs. 8 and 9). The cycle is then repeated.

8 and 9) and oil injection is continued during a desired part of this working stroke. Because of the fact that the two pistons move in the same direction, although at unequal speeds, during this working stroke, the effective piston displacement is substantially double that which a crank of the same eccentricity ordinarily imparts to a single piston.

- 10 The tilt of the connecting rod cross arm causes piston 36 to uncover exhaust ports 34 before the crank pin 11 reaches its lowermost position (Fig. 9). The burnt gases are thus released. The exhaust ports remain open 15 until and after the intake ports 34 are opened (Fig. 4). The cycle thus described is repeated.

While this cycle of operations has been going on a similar cycle is functioning in the lower parts of cylinders 20, 30 and chamber 23, but 180 degrees out of step with the described cycle. It is not necessary to describe the operation in the lower part of the cylinders other than to point out that Fig. 4 25 illustrates the position of the parts at the firing point or point of maximum compression, Fig. 5, the first part of the working stroke, Fig. 6 the end of the working stroke with the exhaust ports 35 open, Fig. 7 scavenging with inlet ports 34 and exhaust ports 35 both open, Fig. 8 the admission of compressed air through ports 34 after ports 35 are closed, and Fig. 9 a part of the compression stroke.

- 35 The engine illustrated in Fig. 10 works on the same principle but in this case there are two pairs of cylinders 20^A, 30^A and 20^B and 30^B with associated parts similar to those shown in Fig. 1 and designated by the same 40 reference numerals with the letters "A" and "B" added thereto. The pistons are connected with the shaft 11 as shown. As the parts and the operation are similar to those hereinbefore pointed out, a specific description 45 of them will not be repeated.

Thus by this compact and extremely simple apparatus, an engine is provided which has the desirable characteristics of a long stroke engine without the undesirable 50 long eccentric, and an engine capable of performing an efficient cycle function.

I intend no limitations other than those imposed by the appended claims.

What I claim is:

- 55 1. An internal combustion engine comprising a pair of cylinders connected at their opposite ends by closed chambers, spaced inlet ports in one cylinder, spaced exhaust ports in the other cylinder, pistons in the cylinders 60 arranged to control said ports, mechanism connecting the pistons arranged to cause them to move out of step and to open and close said ports in desired sequence.

2. An internal combustion engine comprising 65 a pair of cylinders connected at their

opposite ends by closed chambers, spaced inlet ports in one cylinder arranged to communicate with opposite ends of the cylinders, spaced exhaust ports in the other cylinder arranged to communicate with opposite ends 70 of the cylinders, pistons in the cylinders arranged to control said ports, mechanism connecting the pistons arranged to cause them to move out of step and to open an exhaust port before the corresponding inlet port is 75 open and to close said exhaust port before said inlet port is closed.

3. An internal combustion engine comprising a pair of cylinders connected at their opposite ends by closed chambers, spaced inlet ports in one cylinder arranged to communicate with opposite ends of the cylinders, spaced exhaust ports in the other cylinder arranged to communicate with opposite ends of the cylinders, pistons in the cylinders 80 arranged to control said ports, mechanism connecting the pistons arranged to cause them to move out of step and at one part of the cycle to open the exhaust port which communicates with one end of the cylinders 85 before the inlet port which communicates with the same end of the cylinders is open and to close said exhaust port before said inlet port is closed, and to cause said pistons at another part of the cycle, to open the exhaust port which communicates with the other end of the cylinders before the inlet port which communicates with said other end of the cylinders is open, and to close the last mentioned exhaust port before the last 90 mentioned inlet port is closed.

4. An internal combustion engine comprising a pair of cylinders connected at their opposite ends by closed chambers, spaced inlet ports in one cylinder arranged to communicate with opposite ends of the cylinders, spaced exhaust ports in the other cylinder arranged to communicate with opposite ends of the cylinders, pistons in the cylinders arranged to control said ports, mechanism connecting the pistons arranged to cause them to move out of step and to open an exhaust port before the corresponding inlet port is open and to close said exhaust port before said inlet port is closed, and 105 means for injecting oil into said chambers near the opposite ends of the cylinders when the pistons are away from their port controlling positions.

5. An internal combustion engine comprising a pair of cylinders connected at their opposite ends by closed chambers, spaced inlet ports in one cylinder arranged to communicate with opposite ends of the cylinders, spaced exhaust ports in the other cylinder arranged to communicate with opposite ends of the cylinders, pistons in the cylinders arranged to control said ports, mechanism connecting the pistons arranged to cause them to move out of step and at one 110

- part of the cycle to open the exhaust port which communicates with one end of the cylinders before the inlet port which communicates with the same end of the cylinders
- 5 is open and to close said exhaust port before said inlet port is closed, and to cause said pistons at another part of the cycle to open the exhaust port which communicates with the other end of the cylinders before
- 10 the inlet port which communicates with said other end of the cylinders is open, and to close the last mentioned exhaust port before the last mentioned inlet port is closed, and means for injecting oil into said chambers
- 15 near the opposite ends of the cylinders when the pistons are away from their port controlling positions.
6. An internal combustion engine comprising a pair of cylinders connected at their opposite ends by closed chambers, spaced inlet ports in one cylinder, spaced exhaust ports in the other cylinder, pistons in the cylinders arranged to control said ports, a crank shaft, a connecting rod, a cross arm operatively connecting the pistons and arranged to cause them to move out of step, and to open and close said ports in desired sequence.
7. An internal combustion engine comprising a pair of cylinders connected at their opposite ends by closed chambers, spaced inlet ports in one cylinder arranged to communicate with opposite ends of the cylinders, spaced exhaust ports in the other cylinder arranged to communicate with opposite ends of the cylinders, pistons in the cylinders arranged to control said ports, a crank shaft, a connecting rod, a cross arm operatively connecting the pistons and arranged to cause them to move out of step and to open an exhaust port before the corresponding inlet port is open and to close said exhaust port before said inlet port is closed.
45. 8. An internal combustion engine comprising a pair of cylinders connected at their opposite ends by closed chambers, spaced inlet ports in one cylinder arranged to communicate with opposite ends of the cylinders, spaced exhaust ports in the other cylinder arranged to communicate with opposite ends of the cylinders, pistons in the cylinders arranged to control said ports, a crank shaft, a connecting rod, a cross arm operatively connecting the pistons and arranged to cause them to move out of step and at one part of the cycle to open the exhaust port which communicates with one end of the cylinders before the inlet port which communicates with the same end of the cylinders and to close said exhaust port before said inlet port is closed, and to cause said pistons at another part of the cycle to open the exhaust port which communicates with the other end of the cylinders before the inlet port which communicates with said other end of the cylinders is open, and to close the last mentioned exhaust port before the last mentioned inlet port is closed, and means for injecting oil into said chambers near the opposite ends of the cylinders when the pistons are away from their port controlling positions.
55. 11. An internal combustion engine comprising a plurality of inter-communicating cylinders, spaced inlet and exhaust ports in said cylinders, a piston in each cylinder, a crank shaft having a crank, a member connected to said crank and pivotally connected to one of said pistons and slidably connected to the other piston.
60. 12. An internal combustion engine comprising a pair of intercommunicating cylinders, spaced inlet ports in one cylinder and spaced exhaust ports in the other cylinder, a pair of pistons in each cylinder, a
- the inlet port which communicates with said other end of the cylinders is open, and to close the last mentioned exhaust port before the last mentioned inlet port is closed.
9. An internal combustion engine comprising a pair of cylinders connected at their opposite ends by closed chambers, spaced inlet ports in one cylinder arranged to communicate with opposite ends of the cylinders, spaced exhaust ports in the other cylinder arranged to communicate with opposite ends of the cylinders, pistons in the cylinders arranged to control said ports, a crank shaft, a connecting rod, a cross arm operatively connecting the pistons and arranged to cause them to move out of step and to open an exhaust port before the corresponding inlet port is open and to close said exhaust port before said inlet port is closed, and means for injecting oil into said chambers near the opposite ends of the cylinders when the pistons are away from their port controlling positions.

1
crank shaft having a crank, a member connected to said crank and pivotally connected to one pair of said pistons and slidably connected to the other pair of pistons.

- 5 13. An internal combustion engine comprising a pair of cylinders connected at their opposite ends by closed chambers, spaced inlet ports in one cylinder and spaced exhaust ports in the other cylinder, a pair
10 of pistons in each cylinder, means connect-

ing the pistons of each pair, a crank shaft, and means connected to said shaft and pivotally connected to the piston connecting means in one cylinder and slidably connected to the piston connecting means in the 15 other cylinder.

In witness whereof, I hereunto set my hand this 14th day of September, 1920.

WILHELM B. BRONANDER.
